UNITED STATES PATENT OFFICE.

CHARLES H. WOLCOTT, CHARLES O. GOODWYNE, JR., AND EARLY N. GOODWYNE, OF FORSYTH, GEORGIA.

FENDER.

977,991.

Specification of Letters Patent.

Patented Dec. 6, 1910.

Application filed December 6, 1909. Serial No. 531,601.

To all whom it may concern:

Be it known that we, CHARLES H. WOLCOTT, CHARLES O. GOODWYNE, Jr., and EARLY N. GOODWYNE, citizens of the United States, 5 residing at Forsyth, in the county of Monroe, State of Georgia, have invented a new and useful Fender, of which the following is a specification.

This invention has relation to fenders especially adapted to be used in conjunction with open fireplaces and grates and it consists in the novel construction and arrangement of its parts as hereinafter shown and described.

15 The object of the invention is to provide a fender of simple structure in the form of a fireplace attachment which when in position and extended in front of the fire-place will form an effectual barrier to prevent 20 articles such as clothing and so forth from accidentally passing over or upon the flames of a fire in the fire-place or grate.

The fender is in the form of a lazy-tongs structure and includes a supporting bar 25 having means for attachment to the hood of the frame of the fire-place. Said supporting bar is provided with a series of slots of peculiar disposition and configuration which carry rivets forming pivots for the 30 lazy-tongs bars constituting the body portion of the fender and which co-act with the said rivets for automatically holding the lazy-tongs structure in elevated or collapsed condition. A bar is attached to the lower 35 portion of the lazy-tongs structure and is provided with inwardly disposed extremities adapted to bear against the sides of the fire-place frame and serve as means for holding the lower portion of the lazy tongs 40 structure in proper position.

In the accompanying drawings, Figure 1 is a front elevation of a fire place frame with the fender in extended position applied thereto. Fig. 2 is a front elevation of 45 a portion of the said frame with the fender in collapsed position thereon. Fig. 3 is a vertical sectional view of the fender cut on the line 1—1 of Fig. 1. Fig. 4 is an edge view of the bar located at the lower portion 50 of the fender.

The fender is designed to be used as an attachment for a fire place frame 1 having at its upper portion an outwardly disposed hood 2. The body portion of the fender is 55 made up of a series of lazy-tongs levers or

bars riveted together at their points of intersection as shown and adapted to have relative pivotal movement as is usual in such structures.

A supporting bar 4 is provided in the vicinity of each end with hook straps 5 adapted to receive the lower edge portion of the hood 2 and which are provided with set screws 6. The bar 4 is provided at a point intermediate its ends with a relatively short 60 vertically disposed elongated slot 7 and at a portion between one end and the slot 7 with a relatively long horizontally disposed slot 8. At the opposite side of the slot 7 the bar 4 is provided with a relatively long slot 70 9 which in turn is provided in its lower edge and in the vicinity of its outer end with a notch 10. The shank of the rivet 11 forming a portion of the lazy-tongs structure passes through the slot 7, the shank of the rivet 12 75 also forming a part of the said structure passes through the slot 8 and the shank of the rivet 13 passes through the slot 9.

A bar 14 is supported at the lower edge of the lazy-tongs structure by means of a rivet 80 passing through the said structure and the said bar at a point intermediate its ends and by rivets 16 passing through the said structure and located in horizontally disposed elongated slots 17 at the end portions 85 of the said bar 14. The extremities 18 of the bar 14 are laterally disposed with relation to the said bar and are adapted to bear against the outer face of the sides of the fire-place frame 1 and serve as means for spacing the bar and the lazy-tongs structure from the back of the fire place or a grate located therein.

Thus it will be seen that when the fender is in extended position in front of the fire-place that it will effectually ward the accidental admission of fabrics and the like over the back of the fire-place. When it is desired that the fender should be collapsed for the purpose of attending to the fire in the same, the bar 14 is raised which in turn will swing the lazy-tongs bars or levers 3 to the close order position as shown in Fig. 2. As this is done the rivets 12 and 13 move toward the outer ends of the slots 8 and 9 respectively and then by permitting the rivet 13 to enter the notch 10 these parts will be held in collapsed position. When it is desired to extend the fender the bar 14 is moved in an upward direction so that the rivet 13 passes 110

above the notch 10 when the bar 14 may descend after the parts assume the position shown in Fig. 1 of the drawing. By reason of the fact that the elongated slot 7 is vertically disposed the rivet 13 may readily enter the notch 10 and may be readily removed from the same. At those seasons of the year when fire is not needed the fender may be detached from the frame 1 by loosening the 10 set screws 6 carried by the strap hooks 5.

Having described the invention, what we claim as new and desire to secure by Letters Patent is:—

15 A fender comprising a lazy-tongs structure, a supporting bar having at an intermediate point a vertically disposed slot receiving a rivet of the lazy-tongs structure, said bar

having at the opposite sides of the said vertical slot horizontally disposed slots, one of which is provided in its lower edge with a 20 notch, the said lazy-tongs structure having rivets which lie in the said horizontal slots the rivet in the slot provided with the notch adapted to enter said notch to hold the lazy tongs structure in collapsed condition. 25

In testimony that we claim the foregoing as our own, we have hereto affixed our signatures in the presence of two witnesses.

CHARLES H. WOLCOTT.
CHAS. O. GOODWYNE, JR.
EARLY N. GOODWYNE.
